IGNITION DEVICE AND PARTS THEREOF

Whitfield C. Smith, Oneonta, N. Y., assignor to
 Bendix Aviation Corporation, New York, N. Y.,
 a corporation of Delaware

Application December 29, 1948, Serial No. 67,950

2 Claims. (Cl. 315—57)

1

This invention relates to ignition apparatus and more particularly to spark plugs and parts thereof adapted for use in ignition systems of the high frequency and low tension distribution type employed for igniting the gaseous charges in the cylinders of internal combustion engines.

One of the objects of the present invention is to provide a novel transformer unit which is adapted to be enclosed in a casing of a radio shielded spark plug of conventional design, and operatively connected with the center electrode thereof.

Another object of the invention is to provide a novel combination of radio shielded spark plug and step-up voltage transformer unit whereby the danger of ignition failures is materially reduced.

Still another object of the invention is to provide a novel transformer unit for use in a spark plug or the like which has a high degree of efficiency and consumes a minimum of space for its capacity.

A further object is to provide a spark plug which is constructed in a novel manner to give maximum assurance against the presence of moisture and gases which tend to cause deterioration and electrical failure.

A still further object is to provide novel means for insulating electrical parts, such as the high potential winding of a transformer, against nearby conductors which are at ground or similar low potential, such as the shell of a spark plug.

Another object is to provide novel means for insuring proper positioning of an insulated transformer unit in a casing, such as the shielding barrel of a spark plug.

Still another object is to provide novel insulating means which will endure the stresses of tremendous and sustained vibration under widely changing conditions of temperature and pressure.

The above and further objects and novel features of the present invention will more fully appear from the following detailed description when the same is read in connection with the accompanying drawings. It is to be expressly understood, however, that the drawings are for the purpose of illustration only and are not intended as a definition of the limits of the invention.

In the drawings, wherein like reference characters refer to like parts throughout the several views,

Figs. 1 and 2 are end views of the structure illustrated in Fig. 3, the same being taken from the left and right ends, respectively;

2

Fig. 3 is a longitudinal sectional view, with some parts shown in full, of one form of shielded spark plug-transformer combination contemplated by the present invention; and

5 Fig. 4 is a detail view partly in section and with parts broken away of the transformer unit of the embodiment of Fig. 3.

The single embodiment of the invention illustrated in the drawings by way of example comprises a shielded spark plug of the ceramic insulation type now in common use in aircraft internal combustion engines. A tubular metallic shell 10 is provided with threads 11 for engagement with a threaded opening in an engine cylinder (not shown). A tubular insulator 12 of rigid ceramic or other suitable insulating material, such as aluminum oxide, may be supported in the shell by a tubular wedge 13 of relatively malleable metal, such as copper, or by some other

10 suitable known means. A center electrode 14, 15 extends through the bore of insulator 12 into spark gap relation with a so-called ground electrode 16 secured to shell 10 and said bore may be suitably sealed around at least a portion of 15 the center electrode in any of many well known ways. Shell 10 is provided with a metallic radio shielding barrel or tube 17 which surrounds the projecting end of center electrode assembly 12, 14, 15 in spaced relation thereto and extends beyond the end thereof to provide a space or well

20 for receiving a novel transformer unit to be next described.

It is necessary in modern engines to impress a relatively high voltage across the points of the 25 spark plugs, and it has been found highly desirable, in order to reduce electrical losses and operational failures, to confine the high voltage to the immediate vicinity of the spark plug. To this end, it has been proposed to enclose 30 transformers within the shielding barrels of conventional shielded spark plugs. Much difficulty has been encountered, however, in overcoming the many hazards and difficulties which occur by reason of heat, vibration and space limitations.

35 The novel transformer unit contemplated by this invention and the novel manner in which the same is combined with and insulated from the spark plug per se solves these and other problems in a unique and satisfactory manner.

40 In the form illustrated, the step-up transformer or coil is constructed for easy installation or replacement as a self-contained unit in the spark plug shell or barrel 17. Said unit comprises an insulator 18 which is preferably provided with a shallow recess 19 at one end and a deep recess 20 at the other. A cup or bent strip

21 of resilient metal has a press fit in the shallow or inner recess 19 and has secured thereto a spring terminal 22 which makes automatic electrical contact with the inner end 15 of the center electrode of the spark plug during installation. A substantial portion of the larger or outer recess 20 is preferably filled with a metallic core 23 for enhancing the efficiency and capacity of the transformer to reduce losses when a high frequency source of electrical energy is used. Said core may be of powdered metal, such as iron, with a binder of suitable insulating material, such as Bakelite, urea resins, or the like, the same being effective to improve the coupling between the primary and secondary windings.

The secondary winding 24 of the transformer may consist of a single solid or closely wound layer of insulated wire extending approximately the full length of insulator 18. In one satisfactory embodiment, 300 turns of #44 heavy "Formvar" insulated magnet wire were used. The beginning or low potential end of winding 24 is connected to a contact pin 25, and the high potential end is connected to cap 21 and hence to the center electrode 15. In order to reduce electrical losses and the adverse effects of corona to a minimum, this closely or solidly wound secondary coil is covered with a high-resistance electrically-conductive coating (not shown) which may be applied to the winding by dipping and subsequent drying and baking. Such coating may comprise finely divided graphite and lamp black suspended in a resinous base. One suitable formula for the coating material consists of a mixture of 10 grams of Acheson Colloids Corp. dispersion #154 (finely divided graphite suspended in solution with alcohol), 4 grams of lamp black, 50 cc. of a solvent such as toluene, and 40 grams of a resin or varnish such as 1202 Glyptal.

After the coating on the secondary winding has been baked, an insulating sleeve 26 is slipped over it and into engagement with a shoulder formed by an enlarged end portion of insulator 18. A primary winding 27 is space wound on sleeve 26 so as to extend the full length of the secondary winding. The beginning of the primary winding is soldered to contact pin 25 and the other end is electrically connected to a ring 28 on the lower end of sleeve 26. In one suitable embodiment the primary winding consisted of 10 turns of #21 "Formvar" insulated magnet wire, the same being preferably wound in the same direction as secondary winding 24 to provide an automatic transformer hook-up whereby the voltage of the primary is added to the voltage of the secondary. Ring 28, which serves several purposes, comprises a central annular portion, a plurality of projections 29 that yieldably grip the end of the insulating sleeve, and a plurality of flared resilient projections 30 which engage a shoulder 31 on the spark plug shell to provide a ground connection and spring support for sleeve 26 to absorb lengthwise tolerances and hold the transformer unit in position during completion of the assembly.

The transformer assembly above described is preferably secured to a metallic closure element 32 for the upper end of barrel 17. As shown, insulator 18 fits into a recess in the inner face of closure 32 and is held in place by an inwardly spun lip 33 which engages a shoulder on the insulator. The inner end of element 32 fits into the upper end of barrel 17 and is positioned by a flange 34 that engages the upper

end of the barrel. Element 32 may be secured in barrel 17 in an air-tight and moisture-proof manner by spot welding or in some other suitable manner.

5 Pin 25, which together with element 32 forms the male half of a plug and socket type electrical connector, extends through a central opening in said element and the annular space surrounding the pin in said opening is hermetically sealed by a glass-to-metal seal 35 or its equivalent. The inner end of pin 25 is bent through a slot or opening 36 in the side wall of insulator 18 for suitable connection to the adjacent ends of primary winding 27 and secondary winding 24.

10 15 Novel means are provided for further insulating the above described current-carrying elements from barrel 17 and parts connected thereto, said means being adapted to withstand wide variations in temperature and the shock of sustained vibrations or the like without cracking. In the form shown, several layers of woven fiber glass, which is itself an insulator, are wound around sleeve 26 and primary winding 27. These layers preferably extend the full 20 length of said sleeve but may be shorter or longer, if desired. In the completed structure as viewed in Fig. 3, the layers 37 of woven glass fibers are embedded in or impregnated with a mass of insulating material which will set to a rigid compound, but preferably remains a somewhat yieldable and resilient solid. Excellent insulating means are thus provided which also serve as a mechanical binder and shock absorbing buffer for the unit which extends into barrel 17.

25 30 35 After the completed unit illustrated in Fig. 4 is installed in spark plug barrel 17, the structure is thoroughly dried, and the spaces within the barrel are evacuated and filled through an opening 38 with the insulating material 39 in liquid form which will thereafter set as a solid. Preferably, a filling material is used which will set up as a solid through chemical reaction with or without the aid of heat. There are several rubber-like compounds of this type now available, such as polymerized cashew nut shell oil mixed with formaldehyde or a styrene polyester resin. The filling may be effected under vacuum through hole 38 which may be later plugged as shown in Fig. 3. In the interest of clarity 40 45 50 some of the spaces within barrel 17 which are filled with compound 39 are shown with the compound removed.

55 There is thus provided a novel spark plug particularly adapted for use in high frequency and low tension distribution ignition systems for internal combustion engines, the same being so constructed as to operate efficiently for long periods of time with minimum danger of failure in operation. Additionally, there is provided novel insulating means particularly adapted for use in the combination of parts disclosed, the same serving to afford mechanical re-enforcement and support for the parts as well as durable insulation capable of enduring the rigorous tests of year-round operation at all altitudes. The novel manner in which the parts described have been combined conserves space without a corresponding loss of efficiency or reduction in safety factor. The construction 60 65 70 is also such that the coil unit can be removed and replaced if it fails during the useful life of the spark plug per se.

75 Although only a single embodiment of the invention has been illustrated and described in detail, it is to be expressly understood that the

invention is not so limited. For example, various other types of spark plugs which differ specifically in construction from the one illustrated may be used. Various changes may be made in the design and arrangement of the parts illustrated, as well as in the specific materials suggested, without departing from the spirit and scope of the invention.

What is claimed is:

1. Ignition apparatus comprising a tubular metallic shell, an insulated center electrode assembly supported in said shell, a tubular metallic barrel on said shell surrounding and extending beyond the end of said assembly, an end closure for said barrel having a passage therethrough, a contact pin extending through said passage, a glass-to-metal seal in said passage around said pin, an insulated step-up voltage transformer in said barrel comprising a rigid insulator secured to said end closure and having a recess at one end for receiving said pin and a resilient terminal at the other end for electrical engagement with the conducting portion of said assembly, a core of powdered metal with a binding of insulating material in said insulator, a secondary winding on said insulator comprising a closely wound layer of insulated wire, opposite ends of said winding being electrically connected to said contact pin and said terminal, a high-resistance electrically-conductive coating covering said secondary winding, an insulating sleeve surrounding said winding and the projecting end of said assembly, a metallic ring mounted on the end of said sleeve and having resilient extensions contacting said shell, a space wound primary winding on said sleeve around said secondary winding, opposite ends of said primary winding being connected to said pin and said ring, a plurality of layers of woven glass fibers surrounding said primary winding and said sleeve, and a solid yieldable insulating

material filling the remaining space in said barrel and embedding said layers of woven glass fibers.

2. In apparatus of the class described, a tubular metallic barrel having an internal shoulder, an end closure for said barrel, an electrical transformer in said barrel comprising a rigid insulator secured to said end closure, a secondary winding of insulated wire on said insulator, an insulating tube closely surrounding said winding and engaging an external shoulder on said insulator, resilient means under compression interposed between said internal shoulder and the end of said tube nearest said internal shoulder, a primary winding on said tube around said secondary winding, and an insulating mass interposed between said tube and said barrel comprising a plurality of layers of woven insulating threads embedded in rubber-like resilient insulation.
